UNITED STATES PATENT OFFICE.

KARL RÖDER, OF MÜLHEIM-ON-THE-RUHR, GERMANY.

STEAM OR GAS TURBINE.

1,186,438.

Specification of Letters Patent. Patented June 6, 1916.

Application filed July 1, 1915. Serial No. 37,580.

To all whom it may concern:

Be it known that I, KARL RÖDER, a citizen of the German Empire, residing at Goetheplatz 3, Mülheim-on-the-Ruhr, Germany, have invented certain new and useful Improvements in Steam or Gas Turbines, of which the following is a specification.

Turbines having drum shaped shafts have the advantage over wheeled turbines that their shafts have considerably more stability, the critical number of revolutions thereof being considerably higher than the number of revolutions during ordinary running. For heavy loads and high speed, however, these turbines are not suitable on account of the high strain on the drum. The proposition of subdividing the drum in such cases into separate wheels leads to constructions which have the disadvantages peculiar to wheeled turbines.

Through the present invention drum turbines are made suitable for high speed, while still retaining their advantages. In accordance with the present invention blade carriers are built in between the drum and the ends of the shaft, and in the case of double turbines, also between the two drums, which blade carriers are constructed as disks of high peripheral speed. The requirement for these high peripheral speeds in the last stages only, is on account of the high specific volume of the steam, and when required in the first stage, it is in order to keep the pressure and temperature in the housing as low as possible. In the middle-pressure portion, the drums may retain a low peripheral speed and small diameters as full admission of steam or gas is intended. Through this new construction an extraordinarily rigid rotor is provided; the limits for constructing such turbines will be placed higher by means of the corresponding formation of the disks without center boring than those of wheeled turbines with through going shaft and bored disks.

In the accompanying drawings which show several embodiments of the new drum turbine with two or three drum bottoms constructed as disks without central boring, Figure 1 is a longitudinal section of such a turbine having a single drum and a disk at each end. Fig. 2 is a similar view of two drums with end disks and a central disk between the two drums. Fig. 3 is a similar view of a drum having double disks closing one end. Fig. 4, a single drum with a disk

at each end provided with integral journals, Fig. 5, a construction similar to Fig. 4, embodying two disks at one end of the drum, the outer one of said disks having an integral journal thereon, and Fig. 6, an embodiment of the invention in which the elements of Fig. 1 are augmented by additional elements which adapt the engine for high speed running, both forward and backward, and thus render it suitable for such uses as the propulsion of ships.

The rotating portion of the machine is, in Fig. 1, composed of the drum *a*, the disks *b* and *c*, and the shaft journals *d*. The high pressure blades *e* and the low pressure blades *g* are secured on the disks while the middle pressure blades *f* are secured on the drum itself.

The modification disclosed in Fig. 2 differs from the one described, in that the disk *b* is situated centrally between two drums *a* and end disks *c*.

In Fig. 3 a further embodiment of the invention is disclosed in which the low pressure blades *g* which exercise the highest centrifugal force, are secured to two disks *c₂* and *c₃*, attached to the end of the drum. The disks of this embodiment being also without central borings are suitable for the construction of wheels exposed to high stress.

The construction of the drum turbines may also be accomplished by making the disks or one portion of the disks in one piece with the adjacent end of the shaft, thereby accomplishing a simplification in construction. Fig. 4 shows such a modification of the invention. The disks serving as carriers for the high pressure blades *e* and the low pressure blades *g* are not, in this case, secured by screws to the journals *d*, but the journals are here shown as central projections on the central solid portions of the disks *b₁* and *c₁* respectively.

The difference in the construction disclosed in Fig. 5 is that the similarly constructed journal *d* is integral with only the outer one *c₄* of the carriers for the low pressure blades while the other disk *c₅* is made without any such projection.

Fig. 6 shows the employment of the invention in connection with turbines such as those which, when put into use, are made to act through wheel gears, to drive ship-propellers and which therefore must be constructed for great output and high speed of

revolution and arranged both for forward and backward running. In addition to the members described in connection with Fig. 1 and designated by the same letters of reference here, the high pressure disk b_r and the drum a_r are provided for the astern turbine which disk and which drum are fitted with the blades e_r and f_r , respectively. As the astern turbine is built for a smaller output mostly than the forward turbine, a low pressure disk for the astern turbine is not provided in the modification represented in this figure of the drawing.

I claim:—

15 1. In a turbine, a rotor comprising a drum having pressure blades arranged thereupon and a disk, carrying not more than two rows of peripherally attached low pressure blades, fixed to the low pressure end of the drum 20 so as to constitute a head therefor, said

disk being, further, of greater diameter than the drum and the shaft being divided so that the drum lies between its inner ends.

2. In a turbine, a rotor comprising a drum having pressure blades arranged thereupon 25 and a disk, carrying not more than two rows of peripherally attached low pressure blades, fixed to the low pressure end of the drum so as to constitute a head therefor, said disk being of greater diameter than the drum 30 and having its central part extended on the side away from the drum to constitute one end of the shaft.

The foregoing specification signed at Barmen this 15 day of April, 1915.

KARL RÖDER. [L. S.]

In presence of—
HELEN NUFER,
ALBERT NUFER.
